CLAIM

The ornamental design for a firearm stock, as shown and described.

DESCRIPTION

FIG. 1 is bottom, rear, right side perspective view of a firearm stock in accordance with the present disclosure.

FIG. 2 is bottom, rear, left side perspective view of the firearm stock of FIG. 1.

FIG. 3 is a left side elevation view of the firearm stock of FIG. 1.

FIG. 4 is a right side elevation view of the firearm stock of FIG. 1.

FIG. 5 is a rear view of the firearm stock of FIG. 1.

FIG. 6 is a front view of the firearm stock of FIG. 1.

FIG. 7 is a top view of the firearm stock of FIG. 1; and, FIG. 8 is a bottom view of the firearm stock of FIG. 1.

The broken lines in the Figures illustrate portions of the article that form no part of the claimed design.
